UNITED STATES PATENT OFFICE.

JOHN H. STAIR, OF AKRON, OHIO.

HORSESHOE.

SPECIFICATION forming part of Letters Patent No. 734,374, dated July 21, 1903.

Application filed November 13, 1902. Serial No. 131,130. (No model.)

To all whom it may concern:

Be it known that I, JOHN H. STAIR, a citizen of the United States, residing at Akron, in the county of Summit and State of Ohio, 5 have invented a certain new and useful Improvement in Horseshoes, of which the following is a specification.

My invention has relation to a detachable rubber calk for metallic horseshoes, and relates especially to the production of a calk which may be placed on a metallic shoe without skilled labor and which may be removed therefrom and renewed as often as the exigencies of the case demand.

Heretofore an objection has existed to horseshoes involving the use of india-rubber or elastic products on account of the fact that the shoes which contain rubber are not capable of being placed in a blacksmith's furnace to shape them to the particular hoof on which they are to be used.

The objects of my invention are to produce a detachable calk which may be removed from the shoe as sold and the metallic portion of the shoe heated and fitted to exactly the shape of the horse's hoof and then the calks are capable of being placed thereon.

A further object is to produce a calk which may be used both for the toe and heel portions of the shoe and which can be renewed as frequently as they wear out and to firmly secure it in the shoe, so that it cannot become unintentionally removed.

To the accomplishment of the aforesaid objects my invention consists in the peculiar and novel construction, arrangement, and combination of parts hereinafter described and then specifically claimed, reference being had to the accompanying drawings, forming a part of this specification.

In the accompanying drawings, in which similar reference-numerals indicate like parts in the different figures, Figure 1 is a plan view of the heel portion of a horseshoe with my improved calk in position; Fig. 2, a similar view of a horseshoe without the calk; Fig. 3, a section at the line *x* of Fig. 1, and Fig. 4 a section at the line *y* of Fig. 1.

In the drawings, 1 is the heel portion of an ordinary horseshoe, the construction of the toe portion being immaterial to this invention and is not shown. In this heel portion

of the shoe is cut a deep rectangular opening 2, from the rear end of which project two holes 3, (indicated in dotted lines in Fig. 2.) 55 Toward the toe portion of the horseshoe, but connected with the opening 2, is a shallower opening 4, in the bottom of which are two semicircular grooves 5, extending entirely across the bottom portion of the shallow 60 opening 4. Between the semicircular grooves 5 is a screw-threaded hole 6 to receive a screw similarly threaded.

The calk 8 is constructed with a lower portion of the required size to nicely fit in the 65 opening 2, from whence it extends upwardly a distance to be determined, and peculiarly adapted to the requirements of the particular hoof to which the shoe is to be attached.

The upper face of the calk 8 is corrugated 70 or roughened on its upper surface, and the sides are inclined outwardly to meet evenly the outside contour of the heel portion of the horseshoe, thereby making a shoulder with the lower portion, which enters the opening 75 2, thus covering to a certain extent the joint between the rubber and metal. Extending through the lower or base portion of the calk are two parallel wires or rods 9, projecting from each end and vulcanized tightly within 80 the calk. The placing of this calk in the opening 2 is attained in the following manner: The calk 8 is taken in the hand by the operator and the rear portion inserted in the opening 2 and the ends of the wires 9 inserted in the openings 3 in the rearmost part of the horseshoe. This can easily be accomplished by reason of the yielding qualities of the rubber calk. The main or body portion of the calk is then pressed down and the front 90 ends of the wires or rods 9 pressed into the grooves 5 in the shallow opening 4. A plate 10 is then placed in the shallow opening 4, whose thickness is such that when placed to rest upon the wires 9 in the grooves 5 its upper surface will be just flush with the general surface of the bottom face of the horseshoe.

A screw 11 is then passed through the plate 10 and firmly secured into the opening 6 between the wires, thus effectually retaining the 100 calk in place.

It will be noticed that the front and rear portions of the rubber calk project slightly over the metal surrounding the opening 2 to

make as tight a joint as possible to keep out dirt or water from the opening 2. This calk is shown as used in the heel portion of the shoe; but its use is not confined to that place 5 alone; but it may be used with equal efficacy in the toe portion thereof. These calks are designed to be placed in position after the shoe has been cooled following the heating necessary to shape the shoe to the horse's hoof, 10 and they may be removed and replaced by similar calks at any time.

Having thus described my invention, what I claim, and desire to secure by Letters Patent, is—

15 The combination in a horseshoe provided with a vertically-sided recess formed therein, said cavity being provided at one end with horizontal holes in one of the vertical walls of said cavity and having at the other end a

shallower cavity connecting with said major 20 cavity, a body of rubber to enter said major cavity, provided with a head portion larger than the dimensions of said cavity and arranged to overhang said cavity, one or more wires passing through the body portion of 25 said rubber and into said horizontal openings and arranged to rest on the base portion of said shallower cavity, and a plate adapted to fill said shallower cavity, and means to retain said plate and wires in place. 30

In testimony that I claim the above I hereunto set my hand in the presence of two subscribing witnesses.

JOHN H. STAIR.

In presence of—

C. E. HUMPHREY,
MAUDE ZWISLER.
